UNITED STATES PATENT OFFICE

91,800

DESIGN FOR A CONFECTION PACKAGE

Clare Brodnax, Cincinnati, Ohio

Application January 5, 1934, Serial No. 50,323

Term of patent 14 years

To all whom it may concern:

Be it known that I, CLARE BRODNAX, a citizen of the United States, residing in the city of Cincinnati, in the county of Hamilton and State of Ohio, have invented a new, original, and ornamental Design for a Confection Package, of which the following is a specification, reference being had to the accompanying drawing, forming part thereof.

In the drawing:

The figure is a perspective view of my new design for a confection package.

The distinguishing feature of the design is a head formed by a wrapper folded about a large lollipop—the arms are terminated by lollipops having flexible wrappers thereon—the lower portion having a slit therein so that it will hold candy as a bag, and designed to imitate the lower portion of a figure to go with the head and hands.

I claim:

The ornamental design for a confection package as shown and described.

CLARE BRODNAX.
